TOBACCO PIPE RECEPTOR

George N. Polymeros, St. Paul, Minn., assignor of
one-half to Julius Loipersbeck, St. Paul, Minn.

Application July 16, 1948, Serial No. 39,092

3 Claims. (Cl. 131—184)

1

This invention relates to tobacco pipe receptors, and particularly to a receptor having a device, which serves as a revolving cleaner, an air regulator and a mounting clip.

Attachments and burners have been made for tobacco pipes, for the purpose of eliminating objectionable features of pipe smoking. These have accomplished the purpose to a certain extent, but have not been sufficiently practical to prove popular. Ease of removal and cleaning have been lacking, no change in adjustment for ventilation has been provided for, and some have not had sufficient ventilation space surrounding same. Pipes, with the entire bowl made of metal with a removable insert, likewise have accomplished the purpose to a certain extent, but have been lacking in the features above stated and also have been expensive to produce, so have not become very popular. Pipes, with replaceable cartridges to soak up moisture and nicotine, do, with frequent cartridge changes, improve conditions for the smoker, but do not attack the cause of the objectionable features, have a strong smell, and replacing cartridges is a rather messy affair.

One important object of my invention is to provide a tobacco pipe receptor with a device, by which it may be easily removed, instantly cleaned and air circulation regulated.

Another important object is to provide a tobacco pipe receptor with an air space, extending substantially all around it, so that a clean, dry, cool smoke may be enjoyed as a result of such air chamber.

Another object is to provide a tobacco pipe receptor with such desirable features which can be economically manufactured.

Other objects will be apparent from the description and appended claims.

For a full disclosure of my invention, reference is made to the description following and to the drawing, in which—

Fig. 1 is a plan view of a tobacco pipe with my receptor inserted.

Fig. 2 is an elevational view of same, with the bowl of the pipe and the receptor shown in section on line 2—2 of Fig. 1.

Fig. 3 is an elevational view of the receptor removed from the pipe with a part shown in section on line 2—2 of Fig. 1, through a struck in portion.

Fig. 4 is a bottom view of the receptor.

Fig. 5 is an enlarged detail top plan view of only the body portion of the receptor, showing an air circulation channel formed by a struck in portion.

2

Referring more particularly to the drawings I provide a receptor 10 made of thin pressed metal, preferably of aluminum. This receptor has an annular collar 11 extending over the rim of the bowl and has a tapered contour, with a fillet 12, gripping the inside edge of the bowl, so that substantially all of the receptor is enveloped with an air space. Perforations 13 are provided in the receptor of a size to permit sufficient smoking draft, but not large enough to permit particles of tobacco to pass through. A hole 14 in the bottom provides for attachment to the receptor of a member 15. This member serves several purposes. It is shaped to fit closely within the contour of the receptor, and the lower extremity is narrowed as at 15b, and bent after being inserted through the hole 14. This pivots it, permitting easy circumferential movement, instantly cleaning the interior surface of the receptor of any foul substance. It may also be used in this manner, to loosen tobacco that has become too firmly packed in the receptor. This member also serves as an air regulator in conjunction with the ventilation hole 16 by means of the horizontal portion thereof, designated 15a. This hole can be completely or partially covered or left open, by easy adjustment of the member 15. It will be observed, that this hole is provided by punching through a portion of the receptor, that is struck inwardly from the contour of the receptor. In Fig. 3, this struck in portion, which is necessary to form a channel flue, in the otherwise close fit around the edge of the bowl, is indicated in section by numeral 17, and the numeral 16 merely indicates the location of the hole in the rim. Fig. 5 shows a top plan view of this struck in portion and hole on a larger scale. For clarity, the drawings show the member 15a with a slight space, but actually it closes tightly over the hole 16. In lighting up the pipe, it is desirable to close the hole 16, so that smoking draft is increased to well start the burning of the tobacco. As this progresses, the hole may be partially and then fully opened. When drawing smoke, this ventilation hole allows fresh air to come in contact and mix with the smoke coming through the perforations 13, and the smoke is thereby cooled. When the smoker relaxes, the hole 16 acts as a heat outlet and also any moisture, that may be present in the chamber 18, formed between the receptor and the bowl is evaporated and expelled. The smoke duct 19 of the stem is thus kept free from moisture, and since the tobacco in the receptor is kept entirely away from the bottom and removed from the

opening of the smoke duct by the chamber 18, the filth of the combination of nicotine, tobacco and moisture in the bottom of the bowl, clogging the smoke duct, is eliminated. The result is a dry condition, and there is complete combustion without going out, and a burning of tobacco to a clean ash, which is easily removed from the receptor. The member 15 also serves as a mounting clip for the receptor to the pipe, by reason of the bended portion 20. This, besides forming a suitable handle for gripping the receptor for removing or replacing it and for cleaning and regulating, also provides a clip acting against the outside of the pipe bowl to firmly hold the receptor in place. The steel, of which the member 15 is made, has enough springiness to provide the required tension in the bended portion 20, against the outside of the pipe bowl, to hold the receptor securely in place. The receptor can, of course, be turned to any position, so that the ventilation hole 16, and accordingly also the member 15, may be to the front, back or sides of the pipe bowl, the drawings merely showing what might be a preferred position of same.

From the foregoing, it is apparent how my tobacco pipe receptor is constructed, and how it must improve pipe smoking and make it more enjoyable and healthful. All of the tobacco is burned up, and with good aroma from the first to the last puff. There is no accumulation of tobacco, nicotine and moisture to clog the smoke duct of the pipe stem, resulting in an ill-smelling sour pipe, with injurious effects on the smoker. It is a dry, mild smoke, which can be inhaled like that of a cigarette. The smoker is relieved of constant pipe cleaning. The receptor keeps the stem and pipe clean and free from tobacco flakes and slugs. There are no traps for impurities and creators of moisture and strong pipe odor. The ventilation minimizes moisture and odor and keeps the pipe well aired. All that is necessary is to tip out the ashes, revolve the cleaner and refill without resorting to digging out tobacco and thereby clogging the stem of the pipe. The pipe is kept clean with very slight effort.

Also, it is apparent that the receptor can be economically manufactured, since its parts require but a small amount of material and are not difficult to form. A standard size will fit most tobacco pipes, requiring only a little reaming of the bowl. It is thus easily fitted to pipes in stock, the clearance required being provided by slight reaming at a small cost. Otherwise, pipes may in the first instance be manufactured to fit the receptor. Special sizes of receptors can be provided without great increase in manufacturing cost. Since the tobacco or fire does not come in contact with the inner wall of the pipe bowl at any time, the pipe bowl does not burn out, so there is no loss in reaming out the bowl. For the same reason, cheaper woods may be used for pipe making. With the receptor, a better smoke is obtainable regardless of the quality of the wood. The sweeter smoking conventional pipes are made from briar with relatively straight grain, which is quite hard to obtain and expensive. At the same time, such pipe will burn out quicker than one of hard knurly briar, which latter material is cheaper but perhaps more attractive looking. With the receptor therefore, particular woods are not necessary, and it permits the choice of wood and perhaps other kinds of materials, which have an attractive appearance.

While I have shown and described a preferred

form of my invention, it is obvious that many changes, which are within the scope of my invention, will be apparent to those skilled in the art. I therefore desire to be limited only by the scope of the appended claims.

What I claim is:

1. In combination with the bowl of a tobacco pipe, of a receptor and a rotating member, said receptor comprising substantially a thimble-shaped body portion, an annular collar integral with said body portion at the open end thereof and adapted to fit over the rim of the bowl, said body portion leaving substantial air circulation space between it and the inside of the pipe bowl, extending around and under said body portion, said body portion having a fillet adjoining said annular collar, said fillet being of such radius that said receptor is concentrically and firmly suspended in the pipe bowl, said receptor having a plurality of perforations adjacent its lower end having draught communication with the pipe bowl, a hole at its upper end extending through said annular collar and leading directly from and to the atmosphere, said hole being in the top of a flue formed in the otherwise close fit around the edge of the bowl, said hole providing full communication with said air circulation space, said flue consisting of an inwardly struck portion of said receptor, a hole centrally located in the bottom of said receptor, said last mentioned hole being engaged by said rotating member and about which said member is pivoted, said engagement consisting of a narrowed end of said rotating member extending through said last mentioned hole and with a reverse curve bended portion partly within and partly without said receptor to hold same in place, said rotating member having a bended portion over the edge of the pipe bowl with a flat portion fitting tightly over said upper hole and because of such pivoting being adapted to serve as a damper over said ventilation hole and said rotating member having its intermediate portion shaped to conform closely to the interior of said receptor being also adapted to serve as a cleaner of the interior of said receptor, and said rotating member having said bended portion at the upper extremity thereof extending across and downwardly substantially over said pipe bowl, said bended portion having required tension to hold said receptor securely in place although permitting easy movement of said rotating member.
2. In a device of the character described, a thin hollow body member and a rotating member, said body member having tapered sides, an open top and a closed bottom, an outwardly extending annular collar at the open top adapted to fit over the rim of a tobacco pipe bowl, a fillet joining said collar and said body member and concentrically positioned said body member in said pipe bowl and forming a circular chamber intermediate said body member and the inner walls of the pipe bowl and forming a chamber in the bottom of the pipe bowl below the bottom of the body member, said body member having perforations adjacent said bottom and a centrally located opening in said bottom for reception of said rotating member, said perforations providing direct draught connection between said body member and the bottom of said pipe bowl, an opening extending through said annular collar and providing communication between the outside atmosphere and said intermediate chamber in said pipe bowl, said body member having a channel formed in its side to cooperate with said

collar opening to provide full use thereof, said rotating member having a bended portion over the edge of the pipe bowl with a flat portion fitting tightly over said collar opening and retainably pivoting about said opening in the bottom of said body member and adapted to serve as a damper over said opening to the atmosphere in said collar, and said rotating member having its intermediate portion shaped to conform closely to the interior of said body member being also adapted to serve as a cleaner of the interior of said body member, said rotating member having means for providing a handle to conveniently grip same for removing or replacing the body member and also holding the body member firmly in place while still permitting easy movement of said rotating member.

3. In a device of the character described, a tobacco pipe receptor and a rotating member, said receptor having a tapered barrel with perforations adjacent its lower end, a rounded bottom with a central opening to engage and pivot said rotating member, an annular outwardly extending collar with a fillet joining the top of said tapered barrel, an opening in said collar in registry with a channel formed in the upper portion of said barrel, said channel consisting of an inwardly struck portion of said barrel, said receptor being concentrically spaced from the inner wall of a tobacco pipe bowl by said fillet to form an air chamber around and below same, said opening in said collar providing communication between the outside atmosphere and the air chamber, said rotating member being shaped to conform to said tapered barrel and said rounded

bottom as same is rotated and its lower extremity being narrowed and bent in reverse into, through and out of said central bottom opening, its upper extremity extending across and downward over and against the exterior of a pipe bowl, whereby said rotating member serves as a damper over said opening to atmosphere, as a cleaner of the interior of said receptor and to loosen tobacco too firmly packed, and a mounting clip for holding said receptor firmly in said pipe bowl though permitting easy movement of said rotating member, and as a handle to grip receptor for easily removing or replacing same and without being burned.
